ATTORNEY

UNITED STATES PATENT OFFICE.

ALFRED LEANDER RIGGS, OF EBENSBURG, PENNSYLVANIA.

SPARK-PLUG.

1,265,518.

Specification of Letters Patent.

Patented May 7, 1918.

Application filed October 29, 1917. Serial No. 198,941.

To all whom it may concern:

Be it known that I, ALFRED L. RIGGS, a citizen of the United States, residing at Ebensburg, in the county of Cambria and

5 State of Pennsylvania, have invented new and useful Improvements in Spark-Plugs, of which the following is a specification.

This invention relates to spark plugs and has for its object the provision of a spark 10 plug in which it is possible to determine at a glance whether or not current is being fed to the electrodes or being short circuited for any of the usual reasons.

The present invention is an improvement 15 on applications filed October 5, 1916, Serial No. 123,923 and January 23, 1917, Serial No. 143,793.

The primary object of the present invention is to provide a spark plug of the above 20 class in which provision is made for the escape of ozone formed by the electric spark, so as to prevent discoloration of the glass through which the spark is visible.

Another object is to provide novel means 25 for securing the glass in position so as to provide for a slight variation in the diameter of the insulating core of the plug, in order to permit of the assembling of the parts.

30 Other objects and advantages of the invention will be apparent when the following description is read in connection with the accompanying drawings, in which—

Figure 1 is a perspective view of the 35 spark plug embodying the present invention;

Fig. 2 is a transverse sectional view taken through the upper portion of the porcelain core;

40 Fig. 3 is a horizontal sectional view on the line 3—3 of Fig. 2;

Fig. 4 is a detail perspective view of a removable cap;

Fig. 5 is a similar view of the clamping 45 band;

Fig. 6 is a sectional view on the line 6—6 of Fig. 3 illustrating the means for preventing the accidental turning of the securing nut and the terminal block; and

50 Fig. 7 is a detail perspective view of the terminal block.

Referring to the drawings in detail, like characters of reference denote corresponding parts throughout the several views.

55 In the drawings, there is illustrated a spark plug 10, provided with an insulating

core 11, through which extends one of the electrodes 12, the said electrode projecting beyond the surface of the core.

Mounted upon the core 11 is a cap 13, one 60 end of which is provided with an inwardly extending flange 14, which surrounds an opening 15 formed in the cap. This opening is closed by a disk 16 formed of glass or other transparent material, this disk being 65 held in position by means of the retaining ring 17 fitted within the cap 13 and bearing against the under edge of the glass.

The cap 13 is split as shown at 18, in order that it might accommodate itself, to 70 insulating cores of slightly different diameter. This cap is further provided at the end opposite the glass 16 with an outwardly turned flange 18', which is adapted for engagement with one end of a clamping band 19. The band 19 extends around the cap and has formed thereon at diametrically opposite points, inwardly extending engaging lugs 20, which are adapted to engage an annular groove 21 formed in the insulating core 11. The lugs 20 in addition to engaging the groove 21, pass through recesses 22 formed in the flange 18' at diametrically opposite points, these flanges engaging beneath the edge of the cap 13 at these points, 85 while the flange 18' engages beneath the adjacent edge of the band 19, so that when the said band is secured in position the cap will be effectually held in position upon the core. 90

Formed upon the band 19 are oppositely extending parallel portions 23, which are provided with aligned openings 24, a screw 25 being passed through these openings for engagement with a nut 26, by means of 95 which the band is tightly secured upon the cap. Mounted upon the screw 25 is a terminal block 27, which has projecting therefrom a threaded stud 28, a binding nut 29 being positioned upon this stud by means of 100 which the electrical conductor for the feed ring 30 is connected to the plug. Each of the outwardly extending portions 23 are formed with laterally extending locking flanges 31, which are adapted to engage one 105 edge of the nut 26 and the block 27, to hold these elements against turning.

The glass top 16 of the cap 13 is spaced from the top of the insulating core 11, so as to provide an electrode chamber 32, within 110 which extends the electrode 12 previously mentioned and the electrode 33 carried by

the feed ring 30. One of the most important features of the invention resides in providing ventilating means for this chamber, in order to prevent discoloration of the 5 glass 16 by the ozone from the electric spark within this chamber. To this end the sides of the cap 13 are formed with ventilating openings 34, preferably arranged around the cap, the retaining ring 17 also being 10 provided with similar openings, so as to permit of the escape of the ozone and to prevent discoloration of the glass.

It is believed that from the foregoing description when taken in connection with the 15 accompanying drawings, the construction and advantages of the invention will be apparent. The right is reserved to make such changes in the form and proportion thereof as will fall within the scope of the claims 20 hereto appended.

Having described the invention, what is claimed is—

1. In a spark plug, a cap removably mounted upon the insulating core, said cap being slotted to provide adjustment, a clamp 25 carried by said clamp for engagement with said core and means located at the open end of said cap for engagement with the clamp.
2. In a spark plug, a cap removably

mounted upon the insulating core, said cap being slotted to provide adjustment, a clamp for securing the cap upon the core, means carried by said clamp for engagement with said core and means including an outwardly 35 extending flange formed on said cap for engagement with the clamp.

3. In a spark plug, a cap removably mounted upon the insulating core, said core having formed therein a circumferentially 40 arranged groove, a clamp surrounding said cap, means carried by said cap for engagement with said clamp and lugs formed on said clamp for engagement with the groove 45 in the insulating core.

4. The combination with a spark plug provided with a removable cap, of a clamp securing said cap upon said plug, said clamp including outwardly extending terminal 50 portions, an adjusting screw for securing said clamp in position, a terminal block pivotally secured between said terminal portions upon said screw, a nut for holding the screw in position and laterally extending 55 flanges carried by the terminal portions and engageable with one edge of said block and nut.

In testimony whereof I affix my signature.

ALFRED LEANDER RIGGS.
